United States Patent

Des. 241,523

Patented Sept. 21, 1976

241,523

CLOCK OR SIMILAR ARTICLE

Arthur M. Felske, Westport, Conn., assignor to
General Electric Company

Filed May 7, 1975, Ser. No. 575,384

Term of patent 7 years

Int. Cl. D10—01

U.S. Cl. D10—23

FIG. 1.

FIG. 2.

FIG. 3.

FIG. 4.

FIG. 5.

FIG. 1 is a front perspective view of a clock or similar article showing my new design;

FIG. 2 is a front elevational view thereof;

FIG. 3 is a rear elevational view thereof;

FIG. 4 is a left side elevational view thereof, the right side being substantially a mirror image thereof; and

FIG. 5 is a top plan view thereof.

I claim:

The ornamental design for a clock or similar article, as shown and described.
